UNITED STATES PATENT OFFICE.

CHARLES D. LYNCH, OF DETROIT, MICHIGAN.

FLEXIBLE STAFF-HOLDER.

1,013,410.

Specification of Letters Patent.

Patented Jan. 2, 1912.

Application filed December 2, 1910. Serial No. 595,246.

To all whom it may concern:

Be it known that I, CHARLES D. LYNCH, a citizen of the United States, residing at Detroit, in the county of Wayne, State of Michigan, have invented certain new and useful Improvements in Flexible Staff-Holders; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to a holder for flags and pennant staffs, especially designed for use upon boats, but adaptable for other uses, and consists in the construction and arrangement of parts hereinafter more fully set forth and pointed out particularly in the claims.

The object of the invention is to provide a holder for flag staffs and other poles, wherein the arrangement is such as to allow 25 the staff to swing to an incline from a vertical in any direction when encountering an object, such as a low bridge, the boom of a sail, piles at docks and boat landings, and other projections, provision being made for 30 returning the socket member of the holder carrying the staff to a vertical position after the obstruction has been passed, and for varying the tension of the flexible connection between the socket member and base, so 35 as to give the holder the required rigidity.

The above object is attained by the device illustrated in the accompanying drawings, in which:—

Figure 1 is an elevation of a staff holder 40 embodying my invention, showing a staff in the socket member thereof, and illustrating the manner of securing the lower or base member to the deck of a boat, or other support. Fig. 2 is a central longitudinal 45 section through the holder and the base of the staff in the socket member thereof, the upper portion of the staff being broken away. Fig. 3 is an elevation showing the socket member of the holder tilted and the 50 connecting spring between the socket member and base flexed to accommodate said movement, the staff and the lower portion of the base member being broken away. Fig. 4 is a longitudinal sectional view

through the parts of the holder disassembled, the connecting spring appearing in elevation.

Referring to the characters of reference, 1 designates a tubular part which depends from the base member 2 of the holder which 55 is provided with a flat bearing face 3 and with laterally projecting ears or flanges 4 through which screws 5 may be passed to secure the holder to the deck 6 of a boat or to any other support. At the lower end of 60 the tubular member 1, the longitudinal opening 7 therethrough is contracted; the wall of said contracted portion being threaded, as shown at 8. The upper portion 65 of the holder comprises a socket member 9 having a staff socket 10 therein and having a central aperture 11 leading from said socket and extending longitudinally through 70 said member. The lower end of the socket member is provided with a flat face 12 which 75 coincides with the flat face 3 of the base member, so that when said faces are placed contiguous, the members of the holder will stand in axial alinement. The upper end of 80 the opening 11 in the socket member is contracted at its point of communication with the socket 10, and the wall of said member surrounding the contracted portion of said opening is threaded, as shown at 13. The upper and lower members or parts of the 85 holder are connected by a tightly coiled expandable spring 14, the trend of whose coil coincides with the trend of the threads 8 and 13, enabling the parts or members of 90 the holder to be flexibly coupled together by screwing the terminals of said spring into the threaded portions of the openings therethrough, as clearly shown in Fig. 2, 95 whereby the tension of said spring is exerted to normally hold the flat faces 3 and 12 of said parts together and maintain them in axial alinement. It will be noted that the spring is engaged at its terminals only by the threaded portions of the members 100 of the holder, an arrangement which leaves the entire portion of the spring between its ends free to expand under longitudinal strain.

The staff 15 is secured in the socket 10 of the member 9 by means of a collar 16 which 105 screws onto the upper end of the socket member and whose marginal portion 17 around the opening therein, through which

the staff passes, engages a shoulder 18 on the staff, as shown in Fig. 2, to prevent the withdrawal of the staff from the socket. The flexibility of the spring 14 is such that when 5 the staff encounters an obstruction, said spring will yield and allow the socket member of the holder to tilt in any direction, as shown in Fig. 3, and by dotted lines in Fig. 2, thereby relieving the staff from all strain 10 and preventing it becoming broken. After the staff shall have passed free from the obstruction, the tension of said spring will restore the parts to their normal position, as shown in Fig. 1. By connecting the members of the holder together, as shown, the joint between them is rendered universally flexible, whereby the staff is allowed to yield 15 against force applied in any direction. The tension of the spring may be varied to increase or decrease its resisting force by turning 20 the upper socket member so as to screw said spring through the threaded parts, or unscrew it therefrom. When mounted upon the deck 6 of a boat, the tubular member 1 projects through the deck, as shown in Figs. 25 1 and 2. The object in having the tubular member relatively long, as shown, is to enable the use of a spring of such length as to afford the required flexibility.

30 Having thus fully set forth my invention, what I claim as new and desire to secure by Letters Patent, is:—

1. A staff holder comprising a stationary base member, an oscillatory socket member 35 mounted thereon, to tilt a flexible and elastic element connecting said members to effect a universal joint between them, the axis of oscillation of said socket member being at one side of the longitudinal axis of said elastic element to effect a longitudinal stress 40 thereon when the socket member is tilted and means for varying the tension of said flexible member.

2. A staff holder comprising a base member 45 having a flat top, a movable socket member having a flat bottom portion adapted to rest upon the top of the base member, and

a flexible element connecting said members to effect a universal joint between them.

3. A staff holder comprising a base member having a flat top, a movable socket member having a flat bottom portion adapted to rest upon the top of the base member, a flexible spring connecting said members to effect a universally flexible joint between 55 them, and means for varying the tension on said spring.

4. A staff holder comprising a base member, a socket member mounted on the base member in axial alinement therewith, a 60 flexible spring crossing the joint between said members to normally retain the socket member in position, the terminals of said spring being threaded in the base and socket members, respectively. 65

5. A staff holder comprising a base member having an aperture therethrough, a movable socket member mounted on the base member and having a longitudinally extending aperture which normally alines with the 70 aperture through the base member, each of said members having a thread in the wall thereof at one end of the aperture therethrough, and a coiled spring lying within said members and crossing the joint therebetween, the terminals of said spring being screwed into the threaded portions of the 75 openings through said members, respectively.

6. A staff holder comprising a hollow 80 base member, a hollow socket member mounted on the base member, a flexible spring within said members crossing the joint between them, the terminals of said spring being threaded in said members respectively, to enable the tension thereof to be varied by a rotation of one of said members about its axis. 85

In testimony whereof, I sign this specification in the presence of two witnesses.

CHARLES D. LYNCH.
